CLAIM

The ornamental design for a hose hanger, as shown and described.

DESCRIPTION

Cross reference is made to copending U.S. patent application Ser. No. 12/345,935, entitled "Hose Hanger Assembly having Car Wheel Rim Configuration with Removable Cover Structure" by Michael H. Goetz, which is assigned to the same assignee as the present invention, and which is filed on the same date herewith, and the disclosure of such patent application is herein incorporated by reference in its entirety.

FIG. 1 is a perspective view of a hose hanger showing my new design;

FIG. 2 is a front elevational view showing the design for the hose hanger of FIG. 1;

FIG. 3 is a left side elevational view showing the design for the hose hanger of FIG. 1;

FIG. 4 is a top plan view showing the design for the hose hanger of FIG. 1;

FIG. 5 is a right side elevational view showing the design for the hose hanger of FIG. 1;

FIG. 6 is a bottom plan view showing the design for the hose hanger of FIG. 1; and,

FIG. 7 is a rear elevational view showing the design for the hose hanger of FIG. 1.

The broken lines in the drawings represent portions of the hose hanger that are not part of the claim. The broken lines and the structures and features they depict form no part of the claimed design.
